OPERATING MECHANISM FOR SWITCHES

Harrison J. L. Frank, Joseph A. Messing, and William A. Harper, Detroit, Mich., assignors to Bulldog Electric Products Company, Detroit, Mich., a corporation of West Virginia

Original application July 23, 1931, Serial No. 552,684, now Patent No. 1,931,319. Divided and application August 19, 1933, Serial No. 685,972, now Patent No. 1,973,618. Divided and this application August 16, 1934, Serial No. 740,134

1 Claim. (Cl. 200—114)

The inventions of this application relate to operating mechanisms for switches of the base and head type or of the block and receptacle type as they are sometimes known, and this application is a division of our prior application Serial No. 685,972, filed August 19, 1933 now Patent No. 1,973,618, patented September 11, 1934, which is a division of Serial No. 552,684, filed July 23, 1931, now Patent No. 1,931,319, patented Oct. 17, 1933.

The objects of the inventions of this application have been distinctly set forth in Patent #1,931,319, October 17, 1933, of which Patent 1,973,618, Sept. 11, 1934 is a division of which this application is a division and need not here be reviewed. It can be said, however, that it is the purpose of this application to cover a specific embodiment of operating means shown herein and divided out from the prior application. This embodiment will readily be understood by those skilled in the art upon reference to the following description and the accompanying drawing, in which

Figures 1 and 2 are, respectively, an elevation 25 and a top plan view of one embodiment.

Figures 1-2

In this embodiment the fuse holders are supported in the carrier in the nature of a frame of 30 unitary one-piece construction which is guided to move with respect to the base in a rectilinear path, the various parts of the frame being immovable with respect to one another as the frame reciprocates to and from the base. The fuse 35 holders do not move with respect to the carrier, until it is desired to re-fuse them, whereupon all but one of their connections with the carrier may be broken, they then being rotated out of the carrier to expose their fuse clip surfaces. A 40 specific description will now be given.

The fuse holders 160 are connected by straps 161 to form a unit, and these straps are provided with pins 162 received in slots 162a of the bars 163 which have end lugs 164 disposed in slots 165 of the carriers 166. The bars 163 may be drawn inwardly by eccentric 167 disposed in their adjacent ends, these eccentric being operated by the pivotal handle 168. Normally the bars lock the fuse holders to the carrier, but when drawn 45 inwardly, the fuse holders are free of the carrier except at the pin and slot pivotal connections 169,

upon which the holders may be rotated out of the carrier for re-fusing to expose their under surfaces.

The carrier is slidable up and down on the side plates 170, the plates having pins 171 received in the carrier slots 172 for permitting such action. A handle 173 is pivoted to the side plates at 171 and this handle has an extension 174 pivoted to a part 175 which is pivoted to a carrier part and to links 176. These have their free ends slidably disposed in slotted lugs 177, and are surrounded by coiled compression springs 178.

When the handles 173 are rotated towards the end of a unit, that is, from its on position, it moves its extension 174 out of straight line toggle forming alignment with part 175, pivoted to the carrier. The links 176 move upwardly beyond the horizontal and thereupon springs 178 act quickly to throw the carrier up to off position, this action being a quick break action. Reverse movement 20 will furnish a quick make to the on position, as can be readily seen.

Now having described the embodiment disclosed, reference will be had to the following claim for a determination of the scope of the inventions of this application, and it is to be understood that the said invention is to be limited, not to the specific details herein set forth, but only by the scope of the claim which follows.

What we claim is:

In a switch, a base, a fuse carrying head for cooperation therewith, a unitary carrier constructed in the nature of a frame, none of whose parts move relative to one another, means for guiding the carrier to move with respect to the base in a guided rectilinear path to and from the base, the head being pivotally connected to and pivotally supported by the carrier so as to move therewith, resilient means for holding the carrier stationary when the same has been withdrawn from the base, and latch means for latching the head to and rendering it immovable with respect to the carrier and releasable for permitting the head to move pivotally with respect to the carrier, when the carrier has been withdrawn from and is held withdrawn from the base, to expose the fuses of the head for refusing.

HARRISON J. L. FRANK.
JOSEPH A. MESSING.
WILLIAM A. HARPER.
